UNITED STATES PATENT OFFICE

2,364,791

WATER HEATER

William O. Horne, Chicago, Ill., assignor to Rheem Manufacturing Company, Richmond, Calif., a corporation of California

Application November 21, 1941, Serial No. 419,841

7 Claims. (Cl. 122—14)

The invention relates to a water heater and more particularly to the so-called domestic storage type.

An object of the present invention is to provide a water heater of the character described utilizing an oil burner as a source of heat and wherein the float control valve, thermostat and other accessory portions are completely concealed within the body of the jacket surrounding the water heater.

Another object of the invention is to provide an oil burner water heater of the character described in which the oil burner and the float control valve are readily accessible for adjustment or inspection or the like and wherein either of these members may be removed from the heater without disturbing the other.

A further object of the invention is to provide an oil burner water heater of the character described in which the ignition of the oil burner may be more easily and readily effected than in constructions heretofore used.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a front elevation of a water heater constructed in accordance with the present invention.

Figure 2 is an enlarged fragmentary vertical sectional view of the base portion of the water heater.

Figure 3 is a plan cross-sectional view of the water heater taken substantially on the plane of line 3—3 of Figure 2.

Figure 4 is an enlarged perspective view of an insulation shield used in the base construction of the heater.

Figure 5 is a fragmentary side elevation of the supporting means for the oil burner.

Figure 6 is a cross-sectional view showing the lighter door construction and taken substantially on the plane of line 6—6 of Figure 5.

The concealing of the auxiliary controls of an oil burner water heater within the body of such heater presents special problems, particularly in connection with the automatic safety float control valve customarily used with oil burners of

the natural draft type. These float control valves operate, as will be understood, to maintain a constant and uniform oil flow into the burner and to safeguard against flooding of the burner. The natural draft oil burner of the type used in the present construction usually consists of a vaporizing pot and carburetor having a plurality of openings in the wall of the pot for introduction of primary air to the vaporized oil preparatory to passing the oil and air mixture to the burner throat for burning with secondary air added thereto. In the usual operation of the burner only a relatively shallow oil deposit is present in the bottom of the burner, since the rate of vaporization balances the rate of oil input. In the event, however, that the burner should fail to properly operate or the flame become extinguished, oil would continue to flow into the bottom of the burner and eventually reach and overflow through the primary air openings, thus escaping the burner and depositing upon the floor and surrounding area. To prevent such an emergency overflow of oil from the burner, an oil float control valve is provided which operates to automatically shut off the oil flow when the oil reaches a predetermined maximum depth in the burner. To so operate, the float control valve need be mounted in substantially horizontal relation to the burner so that as the oil builds up in the burner, it also builds up in the float control valve, the latter functioning to shut off the oil flow by a trip mechanism released by a float riding the oil level in the float control valve mechanism.

In the construction of a water heater of the storage type, it is obviously desirable to keep the over-all transverse dimension or diameter of the unit small consistent with the volume of the storage tank. Since an oil burner is of considerable size and needs be mounted approximately centrally under the bottom of the water tank, it will be seen that if the float control valve is to be mounted within the confines of the unit and at the same time in side-by-side relation to the burner at the same elevation therewith, the float control valve will of necessity be positioned very close to the burner. Such proximity of these units would ordinarily place the float control valve in a zone of relatively high temperature and in fact far higher than at which the same could be safely operated due to the boiling point and flash point of the oil, and heat expansion of the rather delicate control elements of the safety control valve. To obviate this difficulty and as a principal feature of the present invention,

I provide a separate heat insulated, air cooled, compartment for the float control valve which operates to effectively shield from the latter the intense heat radiated from the walls of the oil burner and the surrounding walls of the base of the heater. By the use of such compartment, the float control valve may be located very close to the oil burner and sufficiently close thereto to enable the inclusion of the float control valve within the body of the heater unit without enlarging the latter over an efficient commercial size to accommodate such inclusion.

With reference to the accompanying drawings, the water heater of the present invention includes a vertically elongated water tank 7, here of cylindrical form and having appropriate hot and cold water pipe connections 8 and 9 connected thereto at the top wall 11 of the tank, and provided with a central flue 12 extending from above the top wall 11 to below the bottom wall 13 of the tank. The tank is also desirably provided with a discharge spud 10 adjacent the bottom wall 13, see Figure 2, for connection of a drain fitting, not shown. The tank is supported in vertical position by a base construction including a base ring 14 supported in elevated position by a plurality of feet 16 and upon which is carried a plurality of uprights or standards 17 which are welded or otherwise secured to the side wall 18 of the tank adjacent the bottom wall 13.

Surrounding the tank wall 18 and covering the tank top wall 11 and extending over the full vertical height of the tank to the base ring 14, is an insulation jacket 19 composed in part of a casing 21 surrounding the side wall 18 of the tank in spaced relation to define an annular chamber 22 therebetween which is filled with a suitable heat insulation material 23, such as asbestos, rock wool, glass wool or the like. Thus the insulation jacket and particularly the outer casing 21 extends down below the bottom wall 13 so as to define therebelow a burner compartment or space 24. Mounted in this space directly under the lower end 26 of the flue and in registration therewith is an oil burner 27 of the natural draft type including as aforementioned a perforated open top pot 28 for receipt and vaporization of oil introduced into the burner by means of an inlet conduit 29 piercing the side wall of the pot adjacent the bottom of the pot. Mounted across the top of the pot is a burner ring 31 having a central burner opening or throat 32 and which is supported on the lower end of the flue with the throat 32 in registration therewith by means of a plurality of bayonet lugs 33 on the top of the burner ring 31 which detachably engage a plurality of pins 34 secured to and projecting outwardly from the flue end 26. A safety overflow pan 36 is secured across the bottom and partially up the sides of the burner pot 28 so as to extend the overflow level of the pot above the lower row of primary air openings 37 in the pot.

Access to the burner may be had by way of an opening 38 formed in the casing 21 below the bottom wall 13 of the tank and at the level of the burner and this opening 38 is of sufficient size to permit the insertion and removal of the burner therethrough. A closure 39, here of segmental cylindrical sheet metal form is provided for the opening 38 and is formed with a parametric flange 41 adapted to slidably telescope into a parametric flange 42 provided by the casing 21 around the opening 38. This closure may be conveniently moved to and from its seated position in the opening by means of knobs or handles 43

at the outer side thereof. Preferably the closure is formed with a plurality of air openings 44 for promoting air circulation through the burner compartment.

- 5 As an important feature of the present construction, I provide for the simple and ready ignition of the burner by way of a lighter opening 46 provided in the lower end 26 of the flue immediately in front of the casing opening 38 and by means of which a match or other ignited mass may be easily dropped into the bottom of the burner without extinguishment of the flame by drafts set up within the burner and flue. This opening is normally closed by a hinged door 47 mounted on the lower end 26 of the flue across the opening 46.

As above noted, I incorporate in the unit an automatic safety flow control valve mechanism 48 which is mounted within the confines of the 20 casing 21 below the bottom wall 13 of the heater at approximately the same elevation as the burner 21. The unit here illustrated is of the type that functions to maintain a uniform flow of oil to the burner and to automatically shut off 25 such flow upon building up of the oil level within the burner to a predetermined depth and is further equipped with a thermostatic control operated by a thermal bulb 49, here clamped onto the side wall 18 of the tank to render the latter responsive to the temperature of the water in the tank. As an important feature of the present invention and as above noted, this float control valve is positioned in a separate compartment 51 recessed within the outer casing 21 of the unit 30 so as to project into the space 24 below the tank bottom wall. The compartment is here defined in part by a heat insulation shield 52, best shown in Figures 3 and 4, and which extends across circumferentially spaced points of the casing 21 35 and cooperates therewith to provide the compartment. The shield member is composed of a pair of horizontally spaced vertically extending walls 53 and 54 which provide therebetween a space for insulation material 56 such as asbestos, 40 rock wool, glass wool or the like and which space is capped by a head wall 57 mounted across the upper ends of walls 53 and 54 and is closed at the bottom by the base ring 14. The casing 21 is provided at the compartment 52 with an opening 58, here extending circumferentially and vertically for the full circumferential and vertical dimension of the shield 52 and is bounded by 45 inturned flanges 59 to which the side edges 61 of the shield walls 53 and 54 are secured. As will be seen from Figures 3 and 4, the circumferentially spaced ends 61 of the shield walls 53 and 54 are joined together at the flanges 59 and extend inwardly from these ends in a divergent fashion to provide the insulation space therebetween. The casing opening 58 registering with the valve compartment 51 is normally closed by a 50 removable door 62 which is preferably of the same general size, shape and construction as the door 39 covering the burner opening 38, and as an important feature of the construction of this door, the same is provided with a plurality of air openings 63 for promoting circulation of cool air through the compartment for removal of heat 55 therein passed through the insulation shield 52. Preferably the door or closure 62 is of thin wall 60 metal construction having a relatively large area whereby the same is effective to radiate any excess heat in the compartment. As will be seen from Figure 2, the base ring 14 defines the bottom of this compartment and the intake and 65 70 75

discharge oil connections 84 and 86 for the float control valve are made through openings in the base ring 14. Preferably these openings are somewhat larger than the conduits passing therethrough so as to leave clearance for passage of air up through the compartment.

I claim:

1. A domestic storage type water heater comprising, an elongated up-ended water tank, an insulation jacket corresponding in form to and surrounding said tank, an oil burner and a float control valve mounted in side-by-side horizontally spaced relation under said tank and within the transverse dimension of said tank and jacket, and partition means defining a compartment close to said oil burner and including heat insulation means mounted between said burner and float control valve.

2. A domestic storage type water heater comprising, an elongated up-ended water tank, a casing surrounding said tank in spaced relation and extending below the bottom of said tank to define a burner space thereunder, an oil burner mounted in said space, means defining a closed compartment recessed from the side of said casing into said space, and a float control valve mounted in said compartment.

3. A domestic storage type water heater comprising, an elongated up-ended water tank, a casing surrounding said tank in spaced relation and extending below the bottom of said tank to define a burner space thereunder, an oil burner mounted in said space, means defining a compartment recessed from the side of said casing into said space and closed from the portion occupied by the burner, a float control valve mounted in said compartment, and cool air circulating means for said compartment.

4. A domestic storage type water heater comprising, an elongated up-ended water-tank, a casing corresponding in form and surrounding said tank in spaced relation and extending below the bottom of said tank, an oil burner mounted below the bottom of said tank within said casing, a float control valve mounted below the bottom of said tank within said casing at approximately the same level as said oil burner, a heat insulation shield connected to and extending across the interior of said casing below said tank bottom to define a closed separate compartment for said float control valve, said casing being formed with an opening at said compartment, and a closure for said opening provided with perforations to promote air circulation through said compartment.

5. A domestic storage type water heater comprising, an elongated up-ended water tank, a casing surrounding said tank in spaced relation and extending below the bottom of said tank, an oil burner mounted under the bottom of said tank, a float control valve positioned adjacent said oil burner in substantially horizontal relation thereto and within the confines of said casing below said tank bottom, heat insulation means mounted between and defining separate compartments for said burner and said float control valve, and a pair of separate access means in said casing below said tank bottom one for the burner and the other for the valve through which said burner and said float control valve may be individually inserted or removed without disturbing the other.

6. A domestic storage type water heater comprising, an elongated up-ended water tank, a casing surrounding said tank in spaced relation and extending below the bottom of said tank, an oil burner mounted under the bottom of said tank, a float control valve positioned adjacent said oil burner in substantially horizontal relation thereto and within the confines of said casing below said tank bottom, heat insulation means mounted between said burner and said float control valve and confining the burner and valve to separate chambers, a pair of separate access means in said casing below said tank bottom communicating with the separate chambers and through which said burner and said float control valve may be individually inserted or removed without disturbing the other, and separate closure means for each of said access means.

7. A water heater comprising, a water tank, a casing surrounding said tank in spaced relation and extending below the bottom wall of said tank, a flue pipe extending through said tank and having a portion depending from said tank bottom wall within the confines of said casing, an oil burner mounted under said flue with the burner throat of said opening in registration with said flue portion, said casing being formed with an opening of a size and position permitting insertion and removal of said burner therethrough, a closure for said opening, said flue portion being provided with a lighter opening directly in front of said casing opening and between said throat and the bottom wall of said tank, and a closure removably covering said lighter opening.

WILLIAM O. HORNE.
